UNITED STATES PATENT OFFICE.

ALFRED E. HUBAND, OF NAUGATUCK, CONNECTICUT.

DESIGN FOR A MUCILAGE-BOTTLE AND BRUSH-CLEANER.

50,974.

Specification for Design.

Patented June 26, 1917.

Application filed April 25, 1917. Serial No. 164,558. Term of patent 3½ years.

To all whom it may concern:

Be it known that I, ALFRED E. HUBAND, a citizen of the United States, residing at Naugatuck, in the county of New Haven and State of Connecticut, have invented a new, original, and ornamental Design for Mucilage-Bottles and Brush-Cleaners, of which the following is a specification, reference being had to the accompanying drawing, forming part thereof.

Figure 1 is a plan view of a mucilage bottle and brush cleaner, showing my new design, and

Fig. 2 is an elevation thereof.

I claim:

The ornamental design for a mucilage bottle and brush cleaner, as shown.

ALFRED E. HUBAND.
